CLAIM

I claim the ornamental design for a wireless home gateway, as shown and described.

DESCRIPTION

FIG. 1 is a front, right side, perspective view of a wireless home gateway in accordance with the present design.

FIG. 2 is a rear, left side, perspective view of the wireless home gateway of FIG. 1.

FIG. 3 is a front view of the wireless home gateway of FIG. 1.

FIG. 4 is a rear view of the wireless home gateway of FIG. 1.

FIG. 5 is a left side view of the wireless home gateway of FIG. 1.

FIG. 6 is a right side view of the wireless home gateway of FIG. 1.

FIG. 7 is a top view of the wireless home gateway of FIG. 1; and,

FIG. 8 is a bottom view of the wireless home gateway of FIG. 1.

The broken lines shown in the figures that are immediately adjacent to the shaded areas and define unshaded regions represent the bounds of the claim. The broken lines within broken line boundaries are directed to environment. The broken lines form no part of the claimed design.
